CLAIM

We claim the ornamental design for a refrigerator door, as shown and described.

DESCRIPTION

FIG. 1 is a perspective view of a refrigerator door showing our new design with its outer door closed;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view with its outer door opened;

FIG. 9 is a front elevation view with its outer door opened;

FIG. 10 is a right-side elevation view with its outer door opened;

FIG. 11 is a top plan view with its outer door opened;

FIG. 12 is a perspective view showing an illustration of use with its outer door closed, the inside thereof being seen;

FIG. 13 is a perspective view showing an illustration of use with its outer door closed, the inside thereof being seen; and,

FIG. 14 is a perspective view showing an illustration of use with each of its inner and outer doors opened.

The broken lines in the drawing figures are included for the purpose of illustrating environment and form no part of the claimed design.
